(57) **CLAIM**

The ornamental design for a panel screen with animated GUI for wearable walking-assistance robot controller, as shown and described.

DESCRIPTION

1. Panel screen with animated GUI for wearable walking-assistance robot controller

1.1 is a front view of a first image of a panel screen with animated GUI for wearable walking-assistance robot controller.

1.2: is a second image thereof.

1.3: is a third image thereof.

The appearance of the transitional image sequentially transitions between the images shown in Figures 1.1, 1.2, and 1.3.

(Continued)

The process or period in which one image transitions to another image forms no part of the claimed design.

The outermost broken lines illustrate a panel screen and form no part of the claimed design. The remaining broken lines illustrate portions of the graphical user interface that form no part of the claimed design.

1 Claim, 3 Drawing Sheets
